JOSEPH ECKERT AND JOHN KIRBY, JR., OF DAYTON, OHIO, ASSIGNEES TO THE DAYTON MANUFACTURING COMPANY, OF DAYTON, OHIO, A CORPORATION OF OHIO.

CAR-BRAKE-OPERATING MECHANISM.

1,266,235.

Specification of Letters Patent. Patented May 14, 1918.

Application filed December 3, 1917. Serial No. 205,082.

To all whom it may concern:

Be it known that we, JOSEPH ECKERT and JOHN KIRBY, Jr., citizens of the United States, and residents of Dayton, in the 5 county of Montgomery and State of Ohio, have invented certain new and useful Improvements in Car-Brake-Operating Mechanism, of which the following is a description, reference being had to the accompanying drawings, which form a part of our 10 specification.

Our invention relates to car brake operating mechanism, and more particularly to that class wherein the handle or operating 15 lever when turned in one direction will rotate the brake-shaft, and when turned in an opposite direction will move independently of the brake-shaft.

The object of our invention is to improve 20 upon the type of brake operating mechanism shown and described in United States Letters Patent issued to Joseph Eckert, No. 1,241,359, September 25, 1917, wherein a ratchet member having teeth formed in its 25 upper surface is fixed to the brake-shaft and a second member in the form of a sliding block, slidably mounted upon the shaft immediately above the said fixed member, the latter being provided with a plurality of 30 longitudinal bores within which plungers operate toward and away from the teeth of the lower fixed ratchet member, a further object of our present invention being to combine certain other features of advantage in 35 that type of brake operating mechanism wherein a ratchet member having teeth formed in its upper face surface is fixed to the brake-shaft and a second ratchet member having corresponding teeth in its lower 40 face surface is slidably mounted upon the shaft, the said upper and lower teeth co-acting to rotate the shaft in a winding direction to set the brakes, while the upper teeth automatically move out of the path of the 45 lower teeth when the operating lever is turned in an opposite direction.

With these objects in view the invention consists in the various novel details of construction and combination of parts herein- 50 after fully described in the specification,

illustrated in the drawings and more particularly pointed out in the claims.

In the accompanying drawings forming part of the specification, and in which like reference characters indicate corresponding 55 parts:

Figure 1 is a side view, partly in full elevation and partly in section through line C C of Fig. 2, the operating lever being shown in full lines in its operative position 60 and by broken lines in its normal or inoperative position, the locking pin being shown in its retainer, Fig. 2 a combined plan and sectional view, the sectional portion being taken on the line B B of Fig. 1, the locking 65 pin being shown in its operative position, Fig. 3 is a partial sectional view through line A A of Fig. 1 showing the device for holding the operating lever against dropping of its own weight, Fig. 4 is a per- 70 spective view of the upper ratchet member, Fig. 5 is a similar view of the lower ratchet member, Fig. 6 is a broken perspective view of the sleeve or casing, and Fig. 7 is a broken side view of the connecting end of the oper- 75 ating lever detached from its support and showing the lift lever mounted thereon.

Referring to the said drawings 1 is the brake-shaft, the lower portion of which is journaled in the car platform in the usual 80 manner. Upon the upper portion of the brake-shaft there is rigidly mounted a ratchet member 2 secured to the shaft, preferably, by means of a pin 3 which passes through the member 2 and the shaft, the 85 upper face of the member 2 being provided with a series of teeth 4. The shaft is reduced at 5, and slidably mounted upon this reduced portion is a second ratchet member 6 having a series of teeth formed in its lower 90 face corresponding with and adapted to engage the teeth in the member 2. The member 6 is circular in form at its lower end and thereabove is formed square, as more clearly shown at 7 in Fig. 4. Surrounding 95 the members 2 and 6 is a sleeve or cylinder member 8 the inside of which is provided with a squared portion 9 corresponding with the square portion 7 of the member 6 and within which the said member 6 slides upon 100

the shaft. At one side of the sleeve member 8 and preferably integral therewith there are lateral ears or extensions 10, 11 upon and between which there is pivotally mounted an operating lever 12 normally suspended upon a pivot bolt 13 which passes through the said extensions and through the operating lever which is thereby adapted to be swung from its normal to a horizontal or operative position as shown more clearly in Fig. 1, this pivot bolt being held against displacement by a head 14 at one end thereof and by a cotter pin 15 at the opposite end. The operating lever is preferably formed hollow having at its connecting end an open space 16 adapted to receive a lift or rocking lever 17 loosely mounted upon the pivot bolt 13 and having a portion extending beyond the end of the operating lever through an opening 18 in the wall of the sleeve 8 into a recess 19 forming a shoulder 20 in the ratchet member 6, the purpose of which will presently appear.

The lift lever 17 is further provided with an arm which extends downwardly from its pivotal center and at an angle thereto and against which arm a projection 21 on the inside of the top wall of the operating lever impinges as the latter drops to its normal position, thereby rocking the lift lever on its pivot and causing the up-turned rounded end 22 thereof to strike the shoulder 20 and thus impart a direct upward movement to the ratchet member 6 to lift the same out of engagement with the member 2 by the downward movement of the operating lever, as shown by dotted lines in Fig. 1.

The brakes are set through a number of partial revolutions of the brake-shaft, that is to say, one stroke of the operating lever, in the direction indicated by the arrow in Fig. 2, will rotate said shaft, say, one-quarter of a revolution, the lever then being reversed for another stroke, the operation being repeated until the brakes are fully set, each partial revolution of the shaft being held against retrograde movement by the usual pawl and ratchet mechanism located on the floor of the platform, which, as it constitutes no part of our invention and is known to all persons familiar with such matters, is not shown in the drawings and need not be further described. It is to be understood that the ratchet member 6, being slidably mounted upon the shaft, operates by gravity to engage the member 2 when the operating lever is in operative position and when so engaged turning of said lever, as before indicated, will rotate the brake-shaft, while in turning the said lever in an opposite direction the member 6 will slide on the brake-shaft and its ratchet teeth will ride over those of the member 2, thus allowing the members 6 and 8 to be rotated in a re-

verse direction independently of the brake-shaft and its fixed ratchet member 2. When the operating lever is in its normal, suspended, position the ratchet members being separated, as hereinbefore explained, the brake-shaft is free to rotate in a reverse direction and unwind the brake chain. 65 70

It sometimes happens that when the brakes are set and the retaining pawl and ratchet located on the car platform, and to which reference has previously been made, is released by the foot of the operator the shaft refuses to unwind because of some irregularity, in such cases it becomes necessary to use force to free the brake chain and allow the shaft to perform its proper function. To provide for such emergency and adapt the mechanism of our present invention to the performance of such reverse action we provide a removable pin 23 adapted to be inserted through perforations 24 in the sleeve 8 immediately above the ratchet member 6 so as to lock the latter in engagement with the ratchet member 2 and thus provide a means whereby the shaft may be operated in a reverse direction by the operating lever. 80 85 A support 25 is provided for the locking pin when out of service and a chain 26 secures it against removal from the brake mechanism. 90

Heretofore, in brake operating mechanism 95 wherein a drop lever has been employed to rotate the brake-shaft the necessity for the operator to exercise a lifting action on the operating lever, when setting the brakes, has been found to be an objection to this type of 100 brake mechanism. To overcome this objection we combine with the mechanism already described means whereby the operating lever when in operative position will be retained therein against the tendency to drop of its own weight, and which a slight pressure exerted on the lever will free the same and permit it to drop by gravity to its normal position. To this end the operating lever is provided with a lateral chamber 27 so located as to be within the space formed between the extensions 10, 11 of the sleeve 8, whatever may be the position of the said lever. Within this chamber there is located a spiral spring 28 having one end bearing 115 against the bottom of the chamber and being provided with a rounded head-piece 29, having a shoulder 30 against which the opposite end of the spring bears and presses the rounded end of the head-piece into a corresponding detent 31 formed in the inner surface of the extension 10 of the sleeve 8. This mechanism is shown, described and claimed in application of John Kirby, Jr., Serial No. 202,142, filed November 15, 1917, 120 it being shown and described in this application merely to illustrate its adaptability to our present invention. 125

To operate the foregoing described brake mechanism the operator raises the operating lever from its normal or inoperative position to its operative or horizontal position, in doing which the upper ratchet member automatically engages the lower ratchet member, thereby establishing operative connection between the brake-shaft and the operating lever when the shaft can be rotated to set the brakes, the operative connection being broken by the dropping of the operating lever, which in swinging to its normal position rotates the lift lever which, in turn, raises the upper ratchet member, as previously described, thereby leaving the brake-shaft free to unwind when not held against retrograde movement by means employed for that purpose.

Having thus fully described our invention, we claim:—

1. In brake operating mechanism, the combination of a shaft, a sleeve mounted on the shaft and adapted to be rotated independently thereof, a lower ratchet member fixed to and rotatable with the shaft within the sleeve and having ratchet teeth formed in its upper face, an upper ratchet member slidably mounted on the shaft having ratchet teeth formed in its lower face corresponding in form and adapted to coact with the teeth of said lower member to rotate the brake shaft said member being rotatable in unison with the sleeve, an operating lever pivotally connected with the sleeve and adapted to rotate the same, and means pivotally mounted on said lever whereby the teeth of said upper ratchet member will be moved out of engagement with those of said lower ratchet member by the dropping of the operating lever to its normal position.

2. In brake operating mechanism a shaft, a fixed ratchet rotatable with the shaft, a ratchet member slidably mounted on the shaft and adapted to positively engage said fixed ratchet, a sleeve mounted on the shaft and rotatable independently thereof, an opening formed in the wall of the sleeve, an operating lever in pivotal connection with the sleeve, a shoulder formed in said ratchet member, a pivoted arm extending from the lever through said opening in the wall of the sleeve and co-acting with said shoulder to disengage the ratchets when the lever is in its normal position, and means whereby the ratchets may be locked in engagement when the lever is in its operative position.

3. In brake operating mechanism, the combination with a shaft adapted to be rotated, of a lower ratchet member fixed to and rotatable with the shaft, an upper ratchet member slidably mounted on said shaft; said ratchet members having teeth of similar form cut therein coöoperating to rotate the

shaft, a sleeve member mounted on the shaft 65 and rotatable thereon in unison with said upper ratchet member independently of the shaft, an operating lever connected with said sleeve member by a pivot bolt and adapted to be swung in and out of operative 70 position thereon, and a lift lever also mounted on said pivot bolt and co-acting with a shoulder formed on said upper ratchet member to lift the same out of operative engagement through the downward movement of 75 the operating lever.

4. In brake operating mechanism, the combination with a shaft adapted to be rotated, of a lower ratchet member fixed to and rotatable with the shaft, an upper ratchet 80 member slidably mounted on said shaft; said ratchet members having teeth cut therein which coöperate to rotate the shaft, a shoulder formed on said upper ratchet member, a sleeve member mounted on the shaft 85 and rotatable thereon in unison with said upper ratchet member independently of the shaft, an operating lever connected with said sleeve member by a pivot bolt and adapted to be swung in and out of operative 90 position thereon, a lift lever also mounted on said pivot bolt and co-acting with said shoulder formed on said upper ratchet member to lift the same out of operative engagement through the downward movement of 95 the operating lever, means for locking the said ratchet members in engagement whereby the shaft may be rotated in a reverse direction.

5. In brake operating mechanism, the 100 combination of a shaft, a sleeve mounted on the shaft and adapted to be rotated independently thereof, a lower ratchet member fixed to and rotatable with the shaft within the sleeve and having ratchet teeth formed 105 in its upper face, an upper ratchet member slidably mounted on the shaft having ratchet teeth formed in its lower face corresponding in form and adapted to co-act with the teeth of said lower member to rotate the brake shaft said member being rotatable in unison with the sleeve, an operating lever pivotally connected with the sleeve and adapted to rotate the same, and a rocking member mounted on said lever and having an upturned rounded end to engage a shoulder formed on said upper ratchet member whereby the teeth of the latter will be moved out of engagement with those of the lower ratchet member by the dropping of 120 the operating lever to its normal position.

6. In brake operating mechanism a shaft, a fixed ratchet rotatable with the shaft, a ratchet member slidably mounted on the shaft and adapted to positively engage said 125 fixed ratchet, a sleeve mounted on the shaft and rotatable independently thereof, an opening formed in the wall of the sleeve, an

operating lever in pivotal connection with the sleeve, a shoulder formed in said ratchet member, a pivoted arm extending from the lever through said opening in the wall of the sleeve and co-acting with said shoulder to disengage the ratchets when the lever is in its normal position, and means intermediate

the top wall of the sleeve and the upper end of said ratchet member whereby the ratchets may be locked in engagement when the lever is in operative position.
